COMBINED RECORD PLAYER AND AMPLIFIER OR SIMILAR ARTICLE

Ken Okabe, Nara, Japan, assignor to Matsushita Electric
Industrial Co., Ltd., Kadoma-shi, Osaka, Japan

Filed Apr. 6, 1971, Ser. No. 131,843

Term of patent 14 years

Int. Cl. D14—01

U.S. Cl. D56—4 R

FIG. 1

FIG. 3

FIG. 1 is a left side, top and front perspective view of a combined record player and amplifier or similar article, showing my new design;

FIG. 2 is a left side, top and front perspective view, the transparent dust cover having been removed and omitted for convenience of illustration; and

FIG. 3 is a right side, bottom and rear perspective view, the transparent dust cover having been removed and omitted for convenience of illustration.

Portions of the figures are shaded to indicate contrast in appearance, and portions are diagonally lined to indicate transparency.

The structure which would be visible through the transparent cover of FIG. 1 has been omitted for convenience in illustration.

I claim:

The ornamental design for the combined record player
